UNITED STATES PATENT OFFICE

WILFRED R. WOOD, OF LONDON, ENGLAND, ASSIGNOR TO INTERNATIONAL COMBUSTION ENGINEERING CORPORATION, OF NEW YORK, N. Y., A CORPORATION OF DELAWARE

ART OF GENERATING STEAM BY THE BURNING OF FUEL IN SUSPENSION

Application filed January 8, 1927. Serial No. 159,968.

This invention relates to improvements in the art of generating steam by the burning of fuel in suspension or space, and is particularly useful where the fuel is in finely divided form, as, for example, powdered coal or coke.

The invention will be described in connection with the burning of pulverized coal. It has heretofore been proposed to introduce powdered coal in an upward direction through the bottom of a combustion chamber. With this type of firing, difficulties have been incurred because of "bird nesting" amongst the boiler tubes, the disadvantages of which are well understood in this art. This difficulty is largely due to the fact that the fuel was admitted substantially in the line of the draft, in consequence of which there were not only objectionable losses in combustible values, but also there was combustion amongst the tubes and other factors contributing to the formation or collection of obstructing deposits on the tubes. It has also been proposed to introduce the fuel horizontally with a vertically widely spreading flame, which is objectionable for substantially similar reasons.

It is one of the objects of my invention to overcome this difficulty, and I am enabled to do so by so admitting the fuel into or near the bottom of the combustion chamber or space that it is, essentially, directed toward the sides of the combustion chamber so as to produce a mushroom flame.

This may, under some conditions of operation, particularly where the boiler is being forced to very high rates, result in destruction of the refractory walls. It is another object of my invention to overcome this difficulty.

A further object of the invention is to prevent destruction of the burner, to which end I propose to cool the burner.

I also propose to provide a preferred arrangement in which the burner is not liable to become clogged up by the deposition of refuse adjacent thereto, to which end I have the burner projecting well up from the bottom or the floor of the combustion chamber, and arrange cooling pipes above the floor, preferably approximately at the level of the

upper end of the burner, said pipes being relatively widely spaced so that gravitating refuse can freely pass therebetween for final deposition on the floor of the combustion chamber.

Another object of the invention is to provide an arrangement which is of simple character, and which, if desired, may be largely standardized by virtue of which existing boiler installations can be readily and effectively converted into high capacity installations.

Insofar as the new boiler installations are concerned, I propose to provide an improved and effective radiant heat boiler of relatively simple construction, small size, and very high capacity, so burning the fuel that maximum radiation is secured.

How the foregoing, together with such other objects and advantages as may herein-after appear, or are incident to my invention, are realized, is illustrated in the accompanying drawings, wherein—

Fig. 1 is vertical section through a boiler furnace illustrating the application of my invention to an existing boiler of a horizontal type.

Fig. 2 is a partial cross section taken on the line 2—2 of Fig. 1.

Fig. 3 is a diagrammatic view illustrating a modification of a detail of my invention, and

Fig. 4 is a vertical section illustrating another embodiment of my invention.

In association with Figs. 1 and 2, I will describe the invention as employed in converting an existing boiler installation, although, of course, it is to be understood that a new installation may be similarly constructed. Referring to these figures, it will be seen that the reference character 7 denotes a horizontal tubular boiler, beneath which is a refractory throat or setting 8 carried on suitable metallic structural work 9. The setting preferably carries the boiler.

Beneath the setting 8 I arrange a unit indicated as a whole by the reference letter A. This unit comprises a preferably circular wall 10, which wall is composed of refractory material, and is of relatively light construction; the ring of exposed substan-

tially upright tubes 11, the upper ends of which pass outwardly through the wall 10 near the top thereof, and the lower ends of which are connected into arcuate headers 12; 5 the screen indicated as a whole by the reference letter *b*; and the burner indicated as a whole by the reference letter *c*; and appropriate downcomer and riser connections to be more specifically described hereinafter. 10 The wall 10 and the tubes 11 define a combustion chamber beneath the setting 8, which latter, in effect, forms a continuation thereof. The floor 13 of the combustion chamber is preferably hopper shaped, as shown, with 15 a number of gate valve controlled outlets 14 for the dumping of refuse. A hollow refractory column rises from the bottom at the center, and within this column is located the burner *c*. This column supports the arcuate 20 headers 16 of the screen *b*. A ring of short pipes 17 connect the arcuate headers 16 with similar arcuate headers 18, such pipes serving to support or position the latter headers from the former headers. Extending radially 25 outward from the headers 18 are relatively widely spaced tubes 19 which connect at their outer ends with the arcuate headers 12. Similar tubes 20 extend radially outward from the headers 16 to arcuate headers 21 located exterior of the combustion chamber. 30

Junction boxes 22—preferably arcuate—are arranged at intervals around the combustion chamber above the headers 21, and are connected to the latter by short tubes 23. 35 The junction boxes are connected by one or more downcomers 24 to a water space of the boiler, such as the bottom portion of the headers 25 thereof. The downcomers 24 are so shaped or arranged that, for all practical 40 purposes, the downcoming water has the same distance to travel from the headers 25 to the junction boxes.

The upper ends of the tubes 11 are connected into arcuate headers 26, which, in turn, 45 are connected by the pipes or tubes 27 to junction boxes 28 similar to the junction boxes 22. The junction boxes 28 are connected by risers 29 to a suitable point of the main boiler, such as the headers 30 thereof, the risers 29 being 50 so arranged that the steam must travel substantially the same distance from all junction boxes 28 to the headers 30.

The circulation is indicated by the arrows. The clean-out plugs 31 for the headers 12 are 55 accessible from the exterior. The clean-out plugs 32 for the headers 18 are made accessible by raising the burner casing 33, which casing is suspended from its upper end on the headers 18. The cleanout plugs 34 for 60 the headers 16 are accessible by raising the burner casting. All other boxes, headers and plugs are exterior of the combustion chamber, and, therefore, readily accessible.

Referring, now, to the burner *c*, this may 65 be of any preferred construction calculated to

tangentially discharge the powdered coal in a direction toward the side walls so as to produce the mushroom flame indicated in the drawings. The burner shown comprises the casing 33 hereinbefore referred to, and the nozzle 35. The coal is fed to the nozzle by carrying air, and is sprayed outward in the manner described mixing with the balance of the air required for combustion, which is preferably supplied through the casing 33. 70 This air may be supplied under pressure by a fan not shown, and may lead from an air preheater not shown. 75

The mushroom flame produced by the burner is a clear intensely hot flame, and, vertically considered, is relatively narrow. This has the following advantages: Better transmission of heat by radiation is secured; the fuel is not discharged in the line of the draft, and combustion is complete within the combustion chamber, so that the loss in combustible values through the boiler is negligible, and honeycombing is prevented. The combustion space is primarily defined by exposed tubes subject to radiant heat, and, therefore, a large capacity is developed. Furthermore, with the hot flame, the rate of heat transmission is higher. In addition, a higher rate of combustion can be maintained with negligible dust loss, say, for example, in the neighborhood of from 30,000 to 35,000 B. t. u.'s. per cubic foot of combustion space. Thus, a relatively small combustion space can be employed and high capacity secured from a relatively small boiler. 95

The tubes 11 protect the wall 10, even if, at very high rates of firing, the flame should happen to impinge thereon. The tubes 11 being upright, rapidly relieve the tubes 19 of the screen of steam, and this, with the downcomer head of water, ensures rapid circulation through the tubes 20 and 19, preventing burning out thereof, as well as securing the benefits of more rapid circulation throughout the entire boiler system. 105 The tubes 11 are preferably finned.

The screen, because of its arrangement, has a very appreciable cooling effect at the center around the burner, and, consequently, the burner is protected. The refuse particles 115 pass freely between the tubes 19 and the tubes 20 and deposit in the hopper shaped bottom, and are readily removed from time to time.

It is also to be noted that the unit A may be largely composed of standard parts which 120 tends to simplicity and economy in manufacture and construction and erection.

If desired, the pipes 17 and 20 and the headers 16 may be dispensed with, and the downcomers 24 led directly to the headers 125 18, as indicated in Fig. 4.

Instead of this latter construction, it may be desirable, in some instances, to arrange the tubes of the screen as indicated in Fig. 3.

The arrangement is also one very well 130

adapted to low set boilers, or to installations where the head room available is small, this, for the reason that a shallow combustion chamber may be employed.

5 Referring now more particularly to Fig. 4, this shows a furnace shaped boiler, i. e., a boiler arranged to define its own combustion chamber. As shown the chamber is rectangular in cross section instead of circular. 10 This and other straight sided arrangements are more economical. The burner or burners may be arranged as before, or in any other way, producing a mushroom-like flame calculated to reduce dust and combustible gas 15 loss.

I claim:

1. In combination, a boiler, a substantially circular combustion chamber therebeneath having side portions thereof lined with exposed tubes in the circulation of the boiler, and burner means at the lower part of the chamber for providing a mushroom shaped flame the axis of which is substantially coaxial with the axis of said chamber, said chamber being also provided with cooling tubes in the circulation of the boiler and extending in proximity to the burner means.

2. A unit for installation under boilers comprising a cage of tubes open at the top, means for connecting the cage into the circulation of the boiler whereby flow takes place through the bottom tubes of the cage and from thence through the side tubes of the cage, said means including downcomer means 35 from the boiler to the cage and upcomer means from the cage to the boiler, a casing for the cage providing an ash receiving space therebelow, and burner means located in the bottom of the cage the axis of the burner 40 means being substantially coaxial with the axis of the cage.

3. In combination, a pulverized coal burning combustion chamber of substantially circular form having metallic, cooled walls, burner means for burning the pulverized coal with a mushroom-like flame, and a water ring of tubes arranged to protect said burner means, the axis of the burner means being substantially coaxial with the axis of the 50 chamber.

4. In combination, a pulverized coal burning combustion chamber of substantially circular form having cooled metallic walls, a water screen in the lower part thereof comprised of spaced water tubes, and burner means at the bottom of the combustion chamber for burning the coal with a mushroom-like flame the axis of which is approximately vertical and coaxial with the axis of the 60 chamber.

5. In combination, a pulverized coal burning combustion chamber of substantially circular form having burner means at the bottom thereof for burning the coal with a mushroom-like flame, the axis of said burner

means being substantially coaxial with the axis of the chamber, and water tubes arranged to create a cool zone below the point of fuel introduction.

6. In combination, a boiler, a substantially circular combustion chamber therebeneath including steam generating elements arranged to constitute the upright walls thereof, spaced steam generating elements defining the bottom thereof, burner means for introducing fuel into said chamber thru an opening in said bottom in a manner to produce a mushroom-like flame, said steam generating elements being connected to deliver the steam generated thereby to the boiler and to receive water from the boiler and the axis of the burner means being substantially coaxial with the axis of the chamber.

7. In combination, a boiler, a substantially circular combustion chamber therebeneath having side portions thereof lined with water tubes in the circulation of the boiler, spaced water tubes in the circulation of the boiler arranged to constitute a bottom screen for the combustion chamber, and burner means at the lower part of the chamber for introducing fuel into the chamber with a mushroom shaped flame, the axis of said burner means being substantially coaxial with the axis of the chamber.

8. In combination, a boiler; a combustion chamber therebeneath having side portions thereof lined with water tubes, water screen tubes at the bottom of said combustion chamber, and a burner at the bottom of the chamber for producing a mushroom flame the axis of which is approximately vertical and coaxial with the axis of the chamber; and headers at each end of the side tubes into which said tubes connect, the water screen tubes connecting at one end into the headers at one end of said side tubes; headers at the other end of the screen tubes into which they connect, said headers being disposed adjacent the burner; downcomer means leading from the boiler to said last mentioned headers, and upcomer means leading from headers of the side tubes to the boiler.

In testimony whereof I have hereunto signed my name.

WILFRED R. WOOD.
